(57) **CLAIM**

The ornamental design for a stud fastener component, as shown and described.

DESCRIPTION

FIG. 1 is a top perspective view of a stud fastener component;

FIG. 2 is a bottom perspective view of the invention illustrated in FIG. 1;

FIG. 3 is a top plan view of the invention illustrated in FIG. 1;

FIG. 4 is a bottom plan view of the invention illustrated in FIG. 1;

FIG. 5 is a front elevation view of the invention illustrated in FIG. 1, wherein the other side elevation views are the same; and,

FIG. 6 is a cross-sectional view of the invention illustrated in FIG. 1.
